UNITED STATES PATENT OFFICE.

OSCAR A. ERICSON, OF CHICAGO, ILLINOIS, ASSIGNOR TO W. W. KIMBALL COMPANY, OF CHICAGO, ILLINOIS, A CORPORATION OF ILLINOIS.

EXPRESSION DEVICE FOR SELF-PLAYING PIANOS.

Application filed December 6, 1920. Serial No. 428,491.

To all whom it may concern:

Be it known that I, OSCAR A. ERICSON, a citizen of the United States, residing at Chicago, in the county of Cook and State 5 of Illinois, have invented certain new and useful Improvements in Expression Devices for Self-Playing Pianos, of which the following is a specification.

This invention relates to what are known 10 as expression devices used on electric or reproducing pianos to automatically effect the playing of a musical composition in conformity with the variations and shading of volume, tone, etc., as indicated or prescribed by the original composer or arranger of the 15 composition. These expression devices, so called, are automatically controlled by the perforated music sheet, the latter having appropriately located slots co-operating 20 with holes in the tracker range, through which latter air is admitted to pneumatics, which latter in turn, through suitable valves govern the volume and power of the 25 exhaust created in the wind chest by the bellows or exhausters.

One object of the present invention is to provide a simple and compact expression device which may readily and conveniently be attached to any reproducing piano and 30 connected up to the wind chest and bellows of the latter, and without involving any modification or alteration of the player action itself. Another object of the invention is to provide an expression device capable of producing a wide range of dynamic 35 effects from pianissimo to fortissimo, and instantly responsive to the control of the record sheet in the yielding of said effects. A further object is to provide an expression 40 device equipped with an automatic stabilizer for normally maintaining a substantially constant vacuum in the wind-chest, regardless of wide variations in the effects produced in the latter by the air admitted 45 through the perforations of the music sheet, except when the several expression controlling devices are called into operation.

Still other objects and advantages of the 50 invention will be apparent to those skilled in the art as the same becomes better understood by reference to the following detailed description, taken in connection with the accompanying drawings in which I have

illustrated one practical and approved embodiment of the invention, wherein—

55

Fig. 1 is a top plan view of the device;

Fig. 2 is a front elevation, with the front cover plate removed to disclose interior parts;

Fig. 3 is a horizontal section, taken on the 60 line 3—3 of Fig. 1, looking from beneath;

Fig. 4 is a vertical section taken on the offset line 4—4 of Fig. 2;

Fig. 5 is a vertical section taken on the 65 line 5—5 of Fig. 1; and

Fig. 6 is a view partly in end elevation and partly in vertical section, taken on the line 6—6 of Fig. 2.

Referring to the drawings—

The housing or casing of the device comprises a generally rectangular built up box-like structure, including a rear wall 10, a removable front wall 11, a top wall 12, a bottom wall 13 and end walls 14 and 15, the end wall 15 comprising in part a relatively wide block centrally cored to form an air passage 16 that communicates directly with a pipe 17 leading to the exhaust pump or bellows of the instrument. The box thus formed is provided with a vertical 80 longitudinal partition 18, forming in rear thereof an air passage 19. The space in front of the longitudinal partition 18 and between the end wall 14 and the block 15 is divided by a transverse partition 20 into 85 two chambers 21 and 22. Into the top wall of the chamber 21 is entered a pipe 21' that leads to the wind-chest of the instrument. In the partition 18 is formed a horizontal oblong port 23 that connects the air passage 90 19 with the chamber 22, and this port is controlled by a throttle valve 24, best shown in Fig. 2, which valve is actuated by pneumatics hereinafter described to vary the size of the air passage between the chambers 19 95 and 22 and thereby regulate the intensity of the suction draft created in the wind-chest by the exhausters.

Mounted upon the casing of the device is a group of pneumatic actions structurally 100 similar to the pneumatic actions commonly employed in player pianos. I have herein shown three such pneumatic actions comprising striking pneumatics 25, 26 and 27, each equipped with the usual diaphragm controlled valve 28, the diaphragm chambers

of these valves being connected by tubes 29, 30 and 31 to expression control openings in the tracker range (not shown) of the instrument. As shown in Fig. 1, the upper swinging side of the pneumatic 25 carries a lateral arm 32 that overlies the upper swinging side of the adjacent pneumatic 26, so that when the pneumatic 25 is collapsed it causes a corresponding collapse to the same extent of the adjacent pneumatic 26. To the upper swinging sides of the pneumatics 26 and 27 are secured forwardly projecting arms 33 and 34, respectively, both of which directly overlie a button 35 carried on the upper end 15 of a rod 36 that extends downwardly through the valve housing and the top wall 12 of the casing, and is connected at its lower end by a pin 37 to the valve 24 at one side of the longitudinal center of the latter. The foldable side of the pneumatic 25 carries a forwardly projecting arm 38 in which is mounted an adjustable stop 39 by which the stroke of the pneumatic is regulated and limited. The arms 33 and 34 carry similar adjustable 25 stops 40 and 41, respectively. The stops are so set that the pneumatic 25 has the shortest stroke; the pneumatic 26 has an intermediate stroke; and the pneumatic 27 has the longest stroke. Manifestly, when the pneumatic 25 30 is collapsed, it operates through the arm 32 to simultaneously collapse the adjacent pneumatic 26 to the same extent, and the latter through its arm 33 striking on the button 35 lowers the right hand end of the valve 24 to an extent permitted by the length 35 of stroke of the pneumatic 25, this latter being limited by the stop 39.

When the pneumatic 26 is collapsed it acts independently of the other pneumatics 40 to similarly affect the valve 24, lowering the latter to a somewhat greater extent permitted by its stop 40. Likewise, when the pneumatic 27 is collapsed it acts to still further lower the valve 24 to the maximum extent as permitted by its stop 41. This lowering of the valve 24 effects varying degrees of opening of the wind port or passage 23.

The pneumatic 25 thus controls the throttle valve 24 to produce a piano effect, the pneumatic 26 similarly controls the throttle valve 24 to produce a mezzo-forte effect, and the pneumatic 27 similarly controls the throttle valve 24 to produce the forte effect. In that portion of the partition wall 18 55 which divides the chamber 21 from the wind passage 19 is formed a port 42 controlled by a disc valve 43, this latter being fast on a valve stem 44 that is slidably mounted at its front end in a bridge 45 and at its rear end 60 in the rear wall 10 of the casing, projecting through the latter and carrying a button 46. This valve 43 is normally held closed by a spring 47 encircling its stem, and is opened by a pneumatic 48 mounted on the outer side 65 of the rear wall. This pneumatic 48 as best

shown in Fig. 5, communicates through ducts 49 and 50 with a diaphragm chamber 51 controlled by a valve 52, this controlling mechanism of the pneumatic 48 being controlled by a hole in the tracker range 70 through a tube 53. When the pneumatic 48 is collapsed, it unseats the valve 43 thereby placing the wind chest of the pneumatic action of the instrument in free communication with the suction bellows through 75 the relatively large port 42, thereby producing the double forte effect.

In the playing of most music records, the vacuum existing in the wind chest of the player action tends to vary according to the 80 number of notes which are being played at successive intervals or periods as the music sheet travels over the tracker range. For instance, a passage containing a large number of notes in both the treble and bass admits a considerable volume of air to the wind chest through the tracker holes and tubes and lowers the vacuum, with a consequent decrease in the force or power with which the notes are sounded by the striking 90 pneumatics of the player action. On the other hand, a solo passage, or a rest or dwell between successive passages involves the admission of little or no air to the wind chest, so that the vacuum in the latter increases, 95 with a consequent increase in the power or force with which the notes are sounded by the striking pneumatics. Hence, it is desirable to provide a stabilizer or pressure governor for the wind chest, which shall act 100 automatically to maintain a substantially constant condition of the vacuum in the wind chest regardless of changes in the volume of sound caused by the note sounding apertures of the music record. 105

In the present invention I have provided such a stabilizer which acts directly upon the main throttle valve 24. To the underside of the casing is attached a pneumatic 54, the lower movable side of which is directly connected by a rod 55 with the left hand end of the throttle valve 24, thus giving to the latter the character of a floating throttle valve. To maintain this valve in close sliding contact with the wall in which 115 its port 23 is formed it is pressed against said wall by a depending spring finger 56 attached at 57 to the top wall of a casing and lying centrally crosswise of the valve 24. As shown in Fig. 4, the interior of the pneumatic 54 communicates freely with the chamber 22 through the port 58.

To provide for an adjustable connection of the pneumatic 54 to the throttle valve 24 through the rod 55, the lower movable 125 side 54' of the pneumatic 54 is slotted as shown at 59, and across this slot extends a bridge 60 itself slotted to permit the passage therethrough of the lower threaded end of the rod 55. On this latter is an ad- 130

justing nut 61 housed within an opening 62 formed through a cleat 63 that is detachably secured to the underside of the pneumatic wing 54' and covers the slot 59. The 5 nut 61 is confined between the bridge 60 and the inner side of a detachable cap 64 which is secured to the lower side of the cleat 63 and is formed with a socket or recess 65 in which the lower end of the rod 55 is housed. Manifestly, by removing the cap 64, the nut 61 may be turned in either direction to thereby lengthen or shorten the 10 effective length of the rod 55, and thereby cause the valve 24 to control a greater or less portion of the port opening 23. The 15 movable wing 54' of the stabilizer pneumatic 54 is normally drawn downwardly or to open position by a pull spring 66 anchored at its upper end at 67 to the free end of the 20 wing 54' and at its lower end to a depending bracket 68 mounted on one end of the main casing. Adjustability of the spring 66, which is of the coil type, is secured in a simple manner by extending the lower end 25 of the spring freely through a hole in the bracket 68, and pivoting to the latter a locking strip 69 which can be swung edgewise between any two adjacent coils of the spring. In the transverse partition 20 which 30 separates the chambers 21 and 22, is a port 70 (Fig. 3) that is guarded by a suspended hinged check valve 71, the purpose of which is to prevent impairment of the vacuum in the wind-chest when the bellows or 35 exhausters are idle.

In the opposite ends of the chamber 22 are a pair of felt blocks 72 and 73 that lie in the plane of the throttle valve 24 and are spaced apart a distance substantially equal 40 to the length of the latter; the purpose of these blocks being to limit the oscillations or vibrations of the valve 24 to the vertical direction, and prevent the valve from swinging endwise.

45 It is believed that the operative principle and mode of action of the expression device will be apparent from the foregoing description. The several pneumatics 25, 26 and 27 when called into action by the music record 50 sheet, by lowering the throttle valve 24, effect varying increases in the effective area of the port 23, correspondingly modifying the vacuum in the wind chest and producing the piano, mezzo forte and forte effects, 55 respectively. The full opening of the valve 43 by the pneumatic 48 places the wind-chest in full communication with the suction through the rear wind passage 19, thereby producing the double forte effect, this being 60 independent of the port 23 and its throttle valve 24.

The manner in which the lower pneumatic 54 operates to stabilize the vacuum in the wind-chest will be apparent when it is 65 considered that the sudden flooding of the

wind chest with a considerable volume of air through the tracker range instantly lowers the vacuum and correspondingly reduces the suction or pull of the exhausters. This reduces the degree of vacuum existing in the pneumatic 54, and the spring 66 instantly acts to open said pneumatic, thereby drawing down the left hand end of the throttle valve 24 and increasing the effective area of the port 23, so that suction 70 acts with greater strength on the wind chest and thus counteracts the lowering of the vacuum in the latter from the tracker range. Conversely, when little or no air enters the wind chest through the tracker range the 80 vacuum rises, and, acting on the pneumatic 54 raises the left hand end of the throttle valve 24 and thereby throttles or chokes the effective area of the port 23. This tends, by reducing the suction, to lower the vacuum. 85 The action of the pneumatic 54 is extremely sensitive and prompt so that it acts at all times to maintain a substantially constant condition of the vacuum in the wind chest insofar as the character of the music record 90 sheet is concerned.

While I have herein shown and described one practical embodiment of my invention which has been found to operate successfully and give the desired expression effects, it 95 will be evident that variations and modifications in the details of structure and relative arrangement of parts may readily be made without altering the principle of operation or sacrificing any of the advantages secured. Hence, I reserve all such modifications as fall within the spirit and purview of the appended claims.

I claim:

1. An expression device for self-playing 105 musical instruments, comprising a box containing a wind passage connected at one end to the wind chest and at the other end to the exhauster, a wall extending across said wind passage and formed with a port, 110 a throttle valve controlling said port, an actuating rod for said valve, a spring urging said valve in port closing direction, a pair of expression pneumatics, stops limiting the power strokes of said expression 115 pneumatics, an arm attached to the movable side of one pneumatic serving to move said valve-actuating rod in a direction to move said valve in port opening direction, and an arm attached to the movable side 120 of the other pneumatic overlying and serving to depress the movable side of its companion pneumatic.

2. An expression device for self-playing 125 musical instruments, comprising a substantially rectangular box containing a wind passage connected at one end to the wind chest and at the other end to the exhauster, a wall extending across said wind passage and formed with a port, a throttle valve 130

controlling said port, an actuating rod for said valve, a spring acting through said rod to urge said valve in port closing direction, a pair of expression pneumatics 5 mounted side by side on the top of said box, adjustable stops differentially limiting the power strokes of said pneumatics, an arm attached to the movable side of one pneumatic serving to depress said valve-actuating rod 10 in a direction to move said valve in port opening direction, and an arm attached to the movable side of the other pneumatic overlying and serving to depress the movable side of its companion pneumatic.

15 3. An expression device for self-playing musical instruments, comprising a substantially rectangular box containing a wind passage connected at one end to the wind chest and at the other end to the exhauster, 20 a wall extending across said wind passage and formed with a port, a throttle valve controlling said port, an actuating rod for said valve extending upwardly through the top wall of said box, a spring acting through 25 said rod to urge said valve in port closing direction, a group of three expression pneumatics mounted side by side on the top of said box, adjustable stops differentially limiting the power strokes of said pneumatics, a pair of arms respectively attached 30 to the movable sides of the center and one side pneumatic and both serving to strike and move said valve actuating rod in a direction to shift said valve in port opening 35 direction, and an arm attached to the movable side of the other side pneumatic overlying and serving to depress the movable side of the center pneumatic.

4. An expression device for self-playing 40 musical instruments, comprising a box containing a wind passage connected at one end to the wind-chest and at its other end to the exhauster, a wall extending across said wind passage and formed with a port, a flat 45 throttle valve pivoted at one end in sliding contact with said wall and partly covering said port, a valve-actuating rod pivoted at its lower end to the other end of said valve and extending through the top wall of said 50 box, a spring urging said rod in an upward direction, a plurality of pneumatics mounted on the top wall of said box, striker arms carried by the movable sides of said pneumatics to depress said rod, and adjustable 55 stops for limiting the strokes of said pneumatics.

5. An expression device for self-playing 60 musical instruments, comprising a box containing a wind passage connected at one end to the wind chest and at the other end

to the exhauster, a wall extending across said wind passage and formed with two independent ports, a throttle valve pivoted at one end in sliding contact with said wall and partly covering one of said ports, a 65 pneumatic mounted on said box and connected to the other end of said throttle valve and operating to swing the latter in a direction to further uncover said port, a valve disc movable toward and from the other of 70 said ports, a spring urging said valve disc to port-closing position, and a pneumatic mounted on said box and operating to unseat said valve disc and open said port.

6. An expression device for self-playing 75 musical instruments, comprising a box containing a wind passage connected at one end to the wind chest and at the other end to the exhauster, a wall extending across said wind passage and formed with two independent ports, a throttle valve pivoted at one end in sliding contact with said wall and partly covering one of said ports, a group of pneumatics mounted on said box and connected to the other end of said 80 throttle valve and operating to swing the latter to varying extents in a direction to further uncover said port, whereby to produce piano, mezzo forte and forte effects, a valve disc movable toward and from the 85 other of said ports, a spring urging said valve disc to port-closing position, and a pneumatic mounted on said box and operating to unseat said valve disc and open said port, whereby to produce a double forte 90 effect.

7. In an expression device for self-playing instruments, the combination of a substantially rectangular box containing a wind 100 passage connected at one end to the wind chest and at the other to the exhauster, a throttle valve controlling said wind passage, a spring urging said valve in a direction to throttle said wind passage, a plurality of expression pneumatics mounted on 105 the top wall of the said box, mechanism differentially operated by said expression pneumatics for moving said valve in a direction to open said wind passage, a pressure governing pneumatic mounted on the 110 lower side of said box in constant communication with said wind passage, a spring opposing collapsing movement of said governing pneumatic, and a connection between said governing pneumatic and said valve by 115 which a collapsing movement of the former transmits a passage-restricting movement to the latter.

OSCAR A. ERICSON.
